UNITED STATES PATENT OFFICE

159,963

CENTER BRACKET SUPPORT FOR A WINDSHIELD VISOR

Richard E. Dieterich, River Forest, Ill.

Application January 25, 1950, Serial No. 7,461

Term of patent 3½ years

(Cl. D14—6)

To all whom it may concern:

Be it known that I, Richard E. Dieterich, a citizen of the United States and resident of River Forest, in the county of Cook and State of Illinois, have invented a new, original, and ornamental Design for a Center Bracket Support for a Windshield Visor, of which the following is a specification, reference being had to the accompanying drawing, forming a part thereof.

Fig. 1 is a perspective view of a center bracket support for a windshield visor embodying my new design.

Fig. 2 is a side elevational view of the same.

Fig. 3 is a top plan view of the same.

I claim:

The ornamental design for a center bracket support for a windshield visor, substantially as shown.

RICHARD E. DIETERICH.
